UNITED STATES PATENT OFFICE.

LEWIS C. LEWIS, OF COLUMBUS, OHIO, ASSIGNOR TO THE MONARCH SPECIALTY MANUFACTURING COMPANY, OF COLUMBUS, OHIO, A CORPORATION OF OHIO.

WATER-MOTOR.

No. 892,531.

Specification of Letters Patent.

Patented July 7, 1908.

Application filed August 14, 1907. Serial No. 388,452.

To all whom it may concern:

Be it known that I, LEWIS C. LEWIS, citizen of the United States, residing at Columbus, in the county of Franklin and State of Ohio, have invented certain new and useful Improvements in Water-Motors, of which the following is a specification.

My invention relates to water motors and has for its object the provision of a device of 10 this character constructed in such manner that it may be very cheaply manufactured and so simply made that but few working parts are provided, whereby the tendency of the motor to get out of order, will be reduced 15 to a minimum.

Further objects and advantages of the invention will be set forth in the detailed description which now follows.

In the accompanying drawings: Figure 1 20 is a vertical section of a motor constructed in accordance with the invention, Fig. 2 is a vertical section upon line $x-x$ of Fig. 1, Fig. 3 is a partial side elevation of the motor, and, Fig. 4 is a detail view of a valve hereinafter 25 described.

Like numerals designate corresponding parts in all of the figures of the drawing.

Referring to the drawing, the numeral 5 designates the base of the motor. Mounted 30 upon this base is a cylinder 6 in which a piston 7 is slidably disposed. This piston is connected to a piston rod 8, said piston rod sliding in a stuffing box 9 of the usual and well known construction. At its outer end 35 this piston rod is connected to any member to be driven such as a rack 10.

A valve casing 11 is mounted at the front end of the motor, said valve casing having an annular chamber 12 formed therein. This 40 chamber is in communication through the port 13 with a by-pass 14. This by-pass communicates with the interior of the cylinder 6 through a port 15. A second port 16 leads from the chamber 12 directly to the 45 forward end of the piston.

A valve which is best illustrated in Fig. 4 is mounted in the valve casing 11. This valve comprises the disks 16 and 17 said disks extending above the body portion 18 50 of the valve and forming an annular channel 19 in the periphery of the valve. At one point about the periphery of the valve, this channel is interrupted by ribs 20 which extend from the body portion 18 outwardly, 55 the outer faces of said ribs lying flush with

the peripheries of the disks 16 and 17. A port 21 is formed between these ribs and communicates with a chamber 22 formed centrally within the valve. An inlet port 23 communicates with this chamber 22, said inlet port being formed in a nozzle 24 which is threaded at 25 into the valve casing 12. A water supply pipe is adapted to be threaded upon this nozzle.

A valve stem 26 passes through the stuffing box 27 carried by the valve casing, said stem being preferably integral with the valve and the valve turning with the stem. Secured by a set screw 28 upon the outer end of this valve stem is an upstanding arm 29 which carries near its outer end a pin 30. Upstanding from the base 5 is a standard 31, upon which an oscillatory member 32 is pivoted as at 33. This member is cut out as at 34 for the reception of the pin 30. One end of 35 a spring 35 is connected to a screw or rivet 36 which is carried by the oscillatory member 32 and the opposite end of said spring is connected to a screw or rivet 37 which is carried by the base 5. An arm 38 projects from the 40 driven member 10 toward the cylinder and at the end nearest the cylinder carries a pin 39, this pin traveling between legs 40 which depend from the oscillatory member 32.

The operation of the device is as follows: 45 Water enters through the inlet port 23 and with the valve in the position illustrated in Fig. 1, flows through the chamber 22 and out through the ports 21 and 16 to the forward end of the cylinder, driving the piston toward 50 the right in said figure. The exhaust from the opposite end of the cylinder is driven out through the port 15, by-pass 14, port 13 and annular channel 19 to the exhaust port 41, from whence it may be conducted 55 by suitable piping to any point. As the piston moves toward the right, the pin 39 strikes the right hand leg 40 in Fig. 3 and throws the upper portion of the oscillatory member 32 to the left until the right hand 60 wall of the cut-out portion 34 strikes against the pin 30. When the screw or rivet 36 moves past the center 33, the spring 35 will act to throw the pin 30 quickly to its limit of movement, pins 42 serving to limit the 65 throw of the arms 40 in either direction. When the pin 30 is thrown over to the left, the arm 29 which carries said pin, will of course likewise be thrown over to the left and will turn the valve stem 26 and the valve to 70

bring the ports 16 into alignment with the port 13. Water from the chamber 22 will then enter the by-pass 14 and from said by-pass will enter the right-hand end of the cylinder in Fig. 1, driving the piston toward the left. Any water contained in the left-hand end of the cylinder will at this time, pass through the ports 16 and into the annular channel 19 and from said annular channel 19 to the exhaust port 41. During this movement of the piston toward the left, the pin 39 will engage the left-hand arm 40 and will begin to move said arm toward the left. This will move the upper portion of the oscillatory member 32 toward the right and after the left hand wall of the cut-out portion 34 contacts with the pin 30 and the screw 36 moves over the center, the spring will act to throw the pin quickly toward the right in Fig. 3. 20 This will throw the valve back to the position illustrated in Fig. 1 and the movement of the piston will again be reversed.

From the foregoing description, it will be seen that simple and efficient means are 25 herein provided for accomplishing the objects of the invention, but while the elements shown and described are well adapted to serve the purposes for which they are intended, it is to be understood that the invention is not limited to the precise construction set forth, but includes within its 30 purview such changes as may be made within the scope of the appended claims.

What I claim, is:

A water motor comprising a cylinder, a piston, a piston rod, a valve casing, an oscillatory valve mounted in said valve casing, means for conducting fluid under pressure to said valve casing, said valve when turned to one of its limits of movement establishing 40 communication between one end of the cylinder and the interior of the valve casing and when turned to its other limit of movement establishing communication between the opposite end of the cylinder and the valve casing, a valve stem, an arm mounted upon the valve stem, a base, a vertical standard carried by said base, a member pivoted to said standard intermediate its ends, said member being bifurcated below its pivotal point to 50 form legs and said member having a cut out portion above its pivotal point, a pin carried by said arm and working in said cut out portion, a member carried by the piston rod and engaging said legs to shift said member, stop 55 members for limiting the movement of said legs in each direction and a spring, one end of which is secured to the base and the other end of which is secured to the pivoted member above its pivotal point.

In testimony whereof I affix my signature in presence of two witnesses.

LEWIS C. LEWIS.
